(57) **CLAIM**

The ornamental design for a chain link, as shown and described.

DESCRIPTION

FIG. 1 is a front perspective view of a chain link showing my new design, showing a symbolic break to indicate indeterminate length;

FIG. 2 is a front view of the chain link shown in FIG. 1; FIG. 3 is a rear view of the chain link shown in FIG. 1; FIG. 4 is a right side view of the chain link shown in FIG. 1;

FIG. 5 is a left side view of the chain link shown in FIG. 1; FIG. 6 is a top view of the chain link shown in FIG. 1; and, FIG. 7 is a bottom view of the chain link shown FIG. 1. The broken line depicting portions of the chain link shows unclaimed subject matter.
